RESILIENT WING MOUNTING AND FRAMING

Herbert Luther Adams, Washington, D. C.

Application November 22, 1932, Serial No. 644,565

8 Claims. (Cl. 244—47)

This invention relates to flying machines, and is a continuation in part of my prior application Serial No. 461,412, filed April 14, 1921, and which now has matured into Patent Number 5 1,888,418, dated November 22, 1932.

One of the objects of the invention is to provide a frame structure for flying machines which possesses maximum strength with minimum weight, and which is capable of a limited amount 10 of flexibility to decrease drag and undue strain on the wings.

A further object of the invention is to provide a frame structure of the character aforesaid which embodies means for changing the dihedral of 15 the wings.

The invention is illustrated in the accompanying drawing, in which:

Figure 1 is a front elevation of a flying machine frame of the folding wing type embodying 20 this invention.

Figure 2 is an enlarged fragmentary longitudinal section through one of the wing struts.

Figure 3 is a view similar to Figure 2 showing a modified form of strut.

Figure 4 is a perspective view showing the invention applied to a flying machine having a conventional type wing.

Referring to the drawing in detail, with particular reference to Figure 4, the numeral 1 indicates a pair of upper fuselage frame members which converge in a rearward direction, and which are rigidly connected at their forward ends by means of a brace 2. Converging rearwardly with respect to the members 1 is a lower fuselage frame member 3 which is rigidly connected at its forward end with the frame members 1 and brace 2 by means of a pair of upwardly diverging braces 4. The braces 2 and 4 provide a triangular frame at the front of the machine having a horizontal top and downwardly converging sides, from which the fuselage frame members 1 and 3 extend rearwardly in the form of a tripod.

Hinged to each of the upper frame members 1, at spaced points lengthwise thereof, is a pair of wing frame members 5 which converge outwardly, and are rigidly connected at their outer ends in any suitable manner. The inner end of the two foremost members 5 are connected with the brace 2, and the inner ends of the two rearmost members 5 are connected with a similar brace 2'. Hinged to the lower frame member 3 at each side thereof is a strut 6 which converges outwardly with respect to the frame members 5, and in connection therewith, forms a tripod projecting laterally from the fuselage frame mem-

bers. The strut 6 is hinged at its outer end to the frame members 5, preferably at a point spaced from the outer ends of the frame members as indicated at 7, although the strut may be extended to the full length of the members 5 if desired. The hinged connections between the wing frame members 5 and upper fuselage frame members 1 are indicated at 5'.

In the embodiment shown in Figure 1, the wings are of the folding type, and the frame members 8, corresponding to the frame members 5 of Figure 4, are provided with a joint 9 having a vertical axis in order that the tip portion 10 may be folded with respect to the main portion of the wing. In this embodiment, the hinged connection between the strut 6 and the wing preferably is adjacent the joint 9.

The strut 6 as shown in Figure 2 comprises a lower hollow section 11, and an upper hollow section 12 slidably extending into the section 11. The section 12 is hinged to the wing frame members 5 in any suitable manner, such as indicated at 7, and the section 11 is hinged to the lower fuselage frame member 3 in any suitable manner, such as by means of a connecting member 13. Movement of the section 12 with respect to the section 11 is limited by means of a pin 14 carried by the section 12 and projecting through a slot 15 in the section 11. The section 12 is normally urged toward its innermost telescoping position with respect to the section 11 by means of a tension spring 16 which has one end connected with the member 13, and its other end anchored to the section 12 by any suitable means such as the connecting means 17. When a lifting force is applied to the wing sufficient to overcome the tension of the spring 16, the section 12 is moved outwardly with respect to the section 11 to permit an increase in the wing dihedral as shown in dotted lines in Figure 1.

Instead of telescoping the upper strut section directly into the lower strut section as shown in Figure 2, the same result may be accomplished by other means such as that shown in Figure 3. In the modified structure shown in Figure 3, the lower section 18 is adapted to be hinged at its lower end to the lower fuselage frame member, and at its upper end is provided with an enlarged extension 19, into which the upper section 20 slidably extends. The upper section 20 is adapted to be hinged at its upper end to the wing frame members, and movement with respect to the lower section is limited by means of a pin and slot in the same manner as heretofore described in con-

nection with Figure 2. Instead of yieldingly urging the upper section inwardly with respect to the lower section as shown in Figure 2, a cable 21 is anchored adjacent the inner end of the section 18, and is extended partially through the section 20 to a pulley 22 rotatably mounted therein. From the pulley 22 the cable 21 passes through a suitable opening 23 in the section 20, from where it is suitably guided to a manually operated control means such as 24 which may be conveniently located within the ready reach of the operator of the flying machine. When it is desired to decrease the wing dihedral, the control means 24 is manipulated to shorten the effective length of the cable 21, and when it is desired to increase the dihedral, the control means 24 is manipulated to pay out the cable to permit outward movement of the section 20 with respect to the section 18 by means of the lifting force of the wing.

Having described my invention, what I claim as new, and desire to secure by Letters of Patent, is:—

1. In a flying machine, a lower fuselage frame member and a pair of upper fuselage frame members converging rearwardly, a pair of outwardly converging wing frame members hinged to and projecting laterally from each of said upper fuselage frame members, and a pair of wing struts hinged to the lower fuselage frame members and each projecting laterally therefrom in converging relation to a pair of said wing frame members, each of said struts including a pair of resiliently connected telescoping parts.

2. In a flying machine, a lower fuselage frame member and a pair of upper fuselage frame members, a pair of wing frame members hinged to and projecting laterally from each of said upper fuselage frame members, and a pair of wing struts hinged to the lower fuselage frame member and each projecting laterally therefrom in converging relation to a pair of said wing frame members and having a hinged connection with the latter.

3. In a flying machine, a lower fuselage frame member and a pair of upper fuselage frame members, a pair of wing frame members hinged to and projecting laterally from each of said upper fuselage frame members, and a pair of wing struts hinged to the lower fuselage frame member and each projecting laterally therefrom in converging relation to a pair of said wing frame members and having a hinged connection with the latter, each of said struts including a pair of telescoping parts.

4. In a flying machine, a lower fuselage frame member and a pair of upper fuselage frame members, a pair of wing frame members hinged to and projecting laterally from each of said upper fuselage frame members, a pair of wing struts hinged to the lower fuselage frame member and each

projecting laterally therefrom in converging relation to a pair of said wing frame members and having a hinged connection with the latter, each of said lower wing frame members including a pair of telescoping parts, and manually operable means for controlling the relative position of said telescoping parts.

5. In a flying machine, a triangular front frame having a horizontal top and downwardly converging sides, a lower fuselage frame member and a pair of upper fuselage frame members connected with said front frame and converging rearwardly, a pair of outwardly converging wing frame members hinged to and projecting laterally from each of said upper fuselage frame members, wing struts having a hinged connection with each of said wing frame members, and means for yieldingly connecting said struts with the lower fuselage frame member.

6. In a flying machine, a lower fuselage frame member and a pair of upper fuselage frame members, a pair of wing frame members hinged to and projecting laterally from each of said upper fuselage frame members, a pair of wing struts hinged to the lower fuselage frame member and each projecting laterally therefrom in converging relation to a pair of said wing frame members and having a hinged connection with the latter, each of said struts including a pair of telescoping parts, one of said telescoping parts having a lengthwise extending slot, and a pin secured to the other telescoping part and extending into said slot.

7. In a flying machine, a lower fuselage frame member and a pair of upper fuselage frame members, a pair of upper wing frame members hinged to and projecting laterally from each of said upper fuselage frame members, a pair of lower wing controllable telescoping frame members, one end hinged to the lower fuselage frame member and each projecting laterally therefrom in converging relation to a pair of said wing frame members and the other end having a hinged connection with the latter, and manually operable means for controlling the relative position of said telescoping parts.

8. In a flying machine, lower fuselage framing means and upper fuselage framing means, wing framing means hinged to and projecting laterally from one of the said fuselage framing means, a controlled resilient telescoping wing strut, one end hingedly connected to another of the fuselage framing means and projecting laterally therefrom and having a converging relation towards said wing framing means, and the other end connected to the latter means, a manually operable means extending within said strut for controlling the relative extension of said telescoping strut parts.
